Patented May 9, 1916.

UNITED STATES PATENT OFFICE.

FRED R. WILLIAMS AND ROBERT B. BENNETT, OF NEWBURGH, NEW YORK.

MECHANICAL TOY.

1,182,126.

Specification of Letters Patent.

Patented May 9, 1916.

Application filed July 28, 1915. Serial No. 42,312.

To all whom it may concern:

Be it known that we, FRED R. WILLIAMS and ROBERT B. BENNETT, citizens of the United States, and residing at Newburgh, in the county of Orange and State of New York, have invented certain new and useful Improvements in Mechanical Toys, of which the following is a specification, such as will enable those skilled in the art to which it appertains to make and use the same.

This invention relates to mechanical toys and game devices, and the object thereof is to provide an improved device of this class representing a war toy or game device, and which is simple in construction, easy of manipulation and comparatively inexpensive, and which will amuse both old and young, and with this and other objects in view the invention consists in a device of the class specified, constructed and operating as hereinafter described and claimed.

The invention is fully disclosed in the following specification, of which the accompanying drawing forms a part, in which the 25 separate parts of our improvement are designated by suitable reference characters in each of the views, and in which:—

Figure 1 is a sectional side view of our 30 complete apparatus indicating the operation; Fig. 2 a partial transverse section on the line 2—2 of Fig. 1; Fig. 3 a plan view of a part of the construction shown in Fig. 1; and, Fig. 4 a partial section on the line 4—4 of Fig. 1, showing the trigger device 35 which we employ.

In Fig. 1 of the drawing, we have shown at *a* a main baseboard or support on one end portion of which is pivoted a cannon device *b* provided with a plunger *b*² operated in 40 one direction by an elastic member *b*³. Pivoted to the rear end portion of the cannon *b* is a trigger device *b*⁴, one end portion *b*⁵ of which is adapted to engage a notch or recess *b*⁶ in the front end portion of the plunger device *b*². The pivotal support of the 45 cannon device *b* consists of a main pin *b*⁷ rotatably mounted in a block *b*⁸ secured to the baseboard *a* in any desired manner, and a smaller pin *b*⁹ is passed through the pin *b*⁷ and the cannon *b*, and this pivotal construction permits both a vertical and horizontal movement of the cannon *b*.

Hinged to the end portion of the baseboard *a* opposite the cannon *b* at *c* is a 50 transverse plate *c*² to the top face of which

are pivoted at *d* a plurality of figures *d*² representing soldiers, in the accompanying drawing, and pivoted inwardly of the plate *c*² and approximately centrally thereof and, as shown at *e*, is a rocker device *e*² provided 60 at one end with a head *e*³ adapted to normally support the free edge portion of the plate *c*², and the other end portion of the rocker device *e*² is provided with a circular head *e*⁴.

Mounted on the baseboard *a* centrally thereof, or approximately so, is a spring-operated yoke *f* pivoted to said baseboard at *f*², and the free end portion of said yoke is provided with a circular plate *f*³, which is 70 mounted in line with the circular head *e*⁴ of the rocker device *e*² and adapted to engage therewith, as indicated in dotted lines in Fig. 1. The yoke *f* is operated by the usual spring construction *f*⁴.

A target device *g* is pivoted to the base *a* at *g*² and provided at its free end with a square face *g*³, and said target device *g* is provided with a projecting member *g*⁴ which is adapted to engage the free end portion of the yoke device *f* to hold it in the position shown in full lines in Fig. 1, said target device being adapted to release the said yoke device so that the spring *f*⁴ thereof will operate said yoke so as to throw it 85 into the dotted line position shown in Fig. 1, said target device being released from said yoke by a projectile *h* discharged from the cannon *b*, as will be readily understood.

Supported adjacent to the rocker device *e*² is a vertical standard *i* adapted to support a roll of detonated cap tape *i*², the end portion of which is placed on the face of the circular head *e*⁴ of the rocker device *e*² so that one or more caps will lie on said face 90 and, in the operation of the yoke device *f*, or when said yoke device is released from its full line position by the target device *g* and thrown into its dotted line position by the spring *f*⁴, the circular plate *f*³ will strike the circular head *e*⁴ with the cap tape thereon thereby producing an explosion at which time the head *e*³ of the rocker device *e*² raises the free edge portion of the plate *c*² so as to throw the figures *d*² backwardly, as indicated in dotted lines in Fig. 1. In other words, when a projectile is discharged from the cannon *b* and strikes the target device *g*, the yoke device *h* is released and strikes one 100 end of the rocker device *e*² and produces an 105 explosion which will throw the figures *d*² backwardly. The baseboard *a* is provided with a 110 transverse slot *a*² through which the baseboard may be moved laterally.

explosion by reason of the cap tape i^2 and the other end is raised so as to knock down the figures d^2 .

Any number of the figures d^2 may be employed and the cannon b or rather the plunger b^2 of the cannon is manipulated in the same manner as other devices of this class, and as the cannon is mounted so as to swing vertically and horizontally it requires skill to manipulate it, and the cannon must be held by one hand and sighted while the plunger is manipulated by the other. In the operation of the cannon, the plunger is pulled back to the limit of its outward movement and the trigger device b^4 is set, after which the cannon is sighted and the trigger device operated to release the plunger.

Our invention is not limited to the exact details of construction herein shown and described, and changes therein and modifications thereof may be made, within the scope of the appended claims, without departing from the spirit of the invention or sacrificing its advantages.

Having fully described our invention, what we claim as new and desire to secure by Letters Patent, is:—

1. In a device of the class described, a baseboard, a movable cannon device supported at one end thereof and adapted to discharge a projectile, a plurality of figures pivotally supported on a transverse plate pivoted to the opposite end portion of said baseboard, said transverse plate being operated by a rocker device pivoted to said baseboard, and a spring-operated device adapted to be held in operative position by a target device, said spring-operated device being released by said projectile striking the said target device whereby said spring-operated device will strike said rocker device so as to raise said transverse plate and knock down said figures.

2. In a device of the class described, a baseboard, a movable cannon device supported at one end thereof and adapted to discharge a projectile, a plurality of figures pivotally supported on a transverse plate pivoted to the opposite end portion of said baseboard, said transverse plate being operated by a rocker device pivoted to said baseboard and a spring-operated device adapted to be held in operative position by a target

device, said spring-operated device being released by said projectile striking the said target device whereby said spring-operated device will strike said rocker device so as to raise said transverse plate and knock down said figures, said spring-operated device being adapted to discharge an explosive in the operation of striking said rocker device.

3. In a device of the class described, a baseboard, a movable cannon device mounted over one end portion of said board, movable members mounted on the opposite end portion thereof and normally held in an upright position, a spring-operated device adapted to be released by a projectile discharged from said cannon device, and means mounted between the spring-operated device and the movable members for throwing said movable members backwardly.

4. In a device of the class described, a baseboard, a movable cannon device mounted over one end portion of said board, movable members on the opposite end portion thereof and normally held in an upright position, a spring-operated device adapted to be released by a projectile discharged from said cannon device, means mounted between the spring-operated device and the movable members for throwing said movable members backwardly, and a detonating member operated by said spring-operated device and said means.

5. In a device of the class described, a baseboard, a movable cannon device mounted on one end portion thereof, a plurality of movable figures mounted on the opposite end portion thereof, a spring-operated device adapted to be released by a projectile discharged from said cannon device, means operated by the spring-operated device for throwing said figures backwardly, and a detonating device operated by the spring-operated device and said means.

In testimony that we claim the foregoing as our invention we have signed our names in presence of the subscribing witnesses this 26 day of July, 1915.

FRED R. WILLIAMS.
ROBERT B. BENNETT.
